DEVICE FOR BREAKING BOTTLES

Joseph Moreng, Grantwood, N. J.

Application April 2, 1936, Serial No. 72,321

2 Claims.

(Cl. 83—93)

In a number of States there are laws which require bartenders to destroy, by partially or wholly breaking, bottles which have contained liquors such as whiskey and gin, as soon as the last of the contents of the bottle has been consumed. Where no machine is available for breaking the bottles the operation is an annoying one and it is also dangerous because of the danger of flying glass injuring the bartender and of the 5 danger of his being cut during the breaking operation and while handling the broken bottle afterwards. Furthermore, in the course of a day there is apt to be a considerable accumulation of 10 broken bottles around the bar, which is objectionable.

The purpose of my invention is to provide a 15 very simple apparatus for breaking enough of the neck of the bottle away to comply with the laws. The apparatus includes an anvil member 20 which is received inside the neck of the bottle and of a member outside the bottle neck which co-operates with the anvil to fracture and remove a portion of the neck of the bottle sufficient to comply with the laws referred to. This exterior member may be operated by hand, preferably through a crank device for applying the required pressure to fracture the neck of the 25 bottle.

The operation may be performed very rapidly 30 and because only a portion of the neck of the bottle need be broken away, there is an accumulation of relatively small quantities of broken glass.

In addition to the fracturing means I have 35 shown in the drawing an enclosing housing for enclosing a neck of a bottle, and the fracturing means to prevent scattering of the fractured glass, so that during the fracturing operation, and even after it, the bartender is not subjected 40 to any liability of injury to his person.

In the fullest embodiment of my invention the 45 housing is provided with a sliding plate having an aperture to receive the neck of the bottle therethrough, the shoulder of the bottle being adapted to rest against the plate to form a complete enclosure, and this plate is movable against the resistance of restoring springs in order that the 50 plate may be moved by the shoulder of the bottle, in order that the neck of the bottle may be applied to the anvil, and in order that bottles having different length necks may all be accommodated.

Another object of my invention is to provide a 55 fracturing device which will operate on all types

of bottle necks and regardless of any surface protrusions such as flanges.

In the drawing forming part of this application,

Figure 1 is a sectional view taken on the line 5 1—1 of Figure 2, showing my invention.

Figure 2 is a front elevation of a bottle breaker embodying my invention.

Figure 3 is a sectional view taken on the line 10 3—3 of Figure 2.

Figure 4 is a sectional view taken on the line 4—4 of Figure 3 showing the bottle neck in position to be fractured.

Figure 5 is a similar view but showing the plunger driven into the position where the bottle 15 is fractured, and

Figure 6 is a perspective view of the plunger and its operating means and the anvil, detached from the remainder of the device.

I prefer to enclose the bottle breaking means 20 within a housing which will receive the neck of the bottle therein and which will prevent the broken glass from scattering during the breaking operation, in order to avoid injury to the operator and to avoid scattering of the glass where it might injure persons coming in contact with it. The housing shown herein may be conveniently bolted to the under side of a bar or it may be mounted independently on a pedestal or otherwise secured in convenient position but in the 25 drawing I have shown the housing bolted and 30 screwed to the under side of a bar.

In the drawing I have indicated a counter or bar at 1 and the housing secured thereto preferably by screws 2 passing through the top wall 35 3 of the housing and entering the under side of the bar. The housing, which is preferably made of metal and which may be in various forms, is shown herein as consisting in part of the top plate 3 which is secured against the under side of 40 the bar as just described. The housing also includes side walls 4 which may be made integral with the top wall and at the bottom of the side walls I have shown inwardly extending bottom walls 5 which have their lower edges turned 45 or bent as shown at 6 and there is a sliding cover 7 for closing the opening through the bottom walls, this cover having its opposite edges turned as shown at 8 to interlock with the turned edges 6 of the bottom walls so that the cover may be 50 slid back to dump the accumulation of broken glass. I have shown the back wall 9 of the housing as made of thicker material, and preferably this is a casting on which the working parts of the bottle breaking device are mounted.

There is a boss 10 extending from the back wall 9 and through this boss extends a rod 11 which is shown as having an enlarged portion 12 forming a shoulder 13 resting against the inner surface of the wall 9 where it is tightly held by means of the screw 14 threaded into the end of the rod member 11 and acting with the washer 15 to draw the member 11 to the right in Figure 3 and thus hold the shoulder 13 tightly pressed against the inner surface of the wall 9.

The enlarged portion 12 forms an anvil adapted to be received within the neck of the bottle as hereinafter described and I preferably mount a hardened stud 16 in a recess in the member 12, this stud having an edge 17 running horizontally or parallel with the axis of the member 12 to serve as a sharp anvil to engage the inner surface of the bore 18 of the bottle 19 presented for breaking. There is a fracturing member which lies outside the neck of the bottle and presses it against the anvil to co-operate therewith in fracturing the neck of the bottle. This outer member is shown as a sliding plunger 20 which is guided to move vertically within a bracket 21 which is attached to the wall 9 the channel within this bracket forming in co-operation with the adjacent portion of the wall 9, a raceway to confine the plunger to a sliding movement at right angles or toward and from the fracturing edge 17 of the anvil.

Preferably, the end of the plunger which engages the neck of the bottle is arched as shown at 22 in Figures 4 and 5 in order that it will come into contact in most cases with the neck of the bottle at the edges 23 or on planes on opposite sides of the plane of the edge 17 so that the action of the plunger and the anvil will cause a fracturing of the glass more readily than if the plunger were in contact with the glass opposite the anvil. This will cause these parts to operate with a minimum of force applied to the operating lever.

Various means may be provided for reciprocating the plunger to fracture the bottle neck but in the drawing I have shown simple means consisting of the following: There is a projecting portion or boss 24 shown as cast integral with the wall 9 and this projection forms part of the bearing for a laterally extending shaft 25 which extends through the projection and which has a collar or nut 26 on one end to prevent the shaft from shifting in one direction; and on the other end there is secured the hub 27 which carries a bent lever arm 28 the forward end of which forms a handle to be grasped by the operator. I have shown a cap 29 bolted against the projection 24 and having a curved groove 30 extending along the same to receive a portion of the shaft 25 therein; and this cap in cooperation with the projection 24 completes the bearing for the shaft. On this shaft there is a crank arm 31 having a rounded end 32 which extends into a recess 33 in the plunger and this crank arm is adapted to cause the movement of the plunger toward and from the anvil.

I have shown the metal forming the walls of the housing bent over at the corners as shown at 34 to provide laterally extending brackets at the front side of the device. I have shown four posts 35 extending through apertures in these corner extensions with the heads 36 of the bolts resting against the outer surfaces of the brackets and the inner ends of these posts are attached to the back wall 9 as by the threads 37 or any other means.

What I prefer to call the front side of the housing is adapted to be closed by a plate 38 which has apertures near its four corners and through which apertures the several posts 35 pass; and this plate is adapted to move along the posts toward and from the back wall.

I have shown a coiled spring 39 surrounding each post and lying between the brackets 34 and the outer side of the plate 38 one end of each spring being attached to one of the brackets and the other end of each spring being attached to the plate 38 so that when the plate is moved from left to right in Figure 3 the movement will be resisted by the coiled springs and when pressure is removed from the plate the springs will move the plate to the left to the full line position shown in Figure 3.

The plate 38 is shown as provided with a centrally located aperture 40 which is of sufficient diameter to permit the neck of the bottle to be inserted therein but still small enough for the shoulder 41 of the bottle to engage the plate and move it toward the right in Figure 3. I estimate that if this aperture is about 3 1/8 inches in diameter it will be appropriate for all bottles which contain spirits or liquors, although I do not wish to confine my invention to any particular proportions.

In order to form a guide for the neck of the bottle I provide a guiding rod 42 in alignment with the anvil and I have shown this as a continuation of the anvil and extending out from the back wall a sufficient distance so that its free end passes slightly through the aperture 40 of the plate 38.

The operation of the device is as follows: Before a bottle is inserted for breakage the plate 38 will be about at the full line or left hand position shown in Figure 3 and in the dotted line position shown in Figure 1 which is its furthest position from the back wall which supports the anvil. When a bottle has been emptied of its contents the bottle is presented to the device so that the neck passes through the opening 40 of the plate 38 and the guiding member 42 is received into the bore of the neck of the bottle.

The bottle is then pressed towards the rear wall 9 and at some point in its movement the shoulder 41 of the bottle will engage the outer side of the plate 38, and from then on the movement of the bottle will cause this plate to move from left to right in Figure 3. The bottle will be pushed back until the end of the neck rests against the back wall 9 and when this occurs the anvil and its breaking member 16 will be received into the open end of the neck of the bottle as shown in Figure 3.

The bottle having thus been positioned, the operator will press down on the lever arm 28 so that the lever arm rocks the shaft 25 and this will cause the crank arm 31 to move the plunger 20 downwardly in Figure 3 and as it does so the edges 23 will first come into contact with the outer surface of the neck of the bottle and as pressure is exerted on the lever arm 28 the action of the end of the plunger in co-operation with the fracturing member 16 on the anvil will cause the single thickness of glass lying between the plunger and anvil to be fractured more or less in the manner shown in Figure 5. That is to say, a piece of the neck of the bottle will be broken away leaving the neck of the bottle imperfect. This is sufficient to render the bottle imperfect and it is sufficient to comply with the laws of the different States requiring breakage

of the bottles after the contents have been dispensed.

Thus the bottle as a whole is not broken up so that the free glass created by the operation is

5 small in quantity and it will fall to the bottom of the housing where it will accumulate in the chamber 45. This chamber may be emptied after a number of bottles have been broken by simply sliding over the bottom cover 7 and allowing the broken glass to fall into a receptacle of any kind. The bottle, after being broken in the manner described herein, is not dangerous to handle, so that in dispensing the bottles the attendant is not apt to injure the hands.

15 As soon as the fracturing operation has been completed, the bottle may be withdrawn from right to left in Figure 3, and disposed of in any desired manner.

The purpose of the sliding plate 39 is to complete 20 the enclosure by the housing so that no part of the glass which is broken from the bottle will fly from the housing. This plate is made movable so that it will remain in contact with the shoulder of the bottle and leave no opening 25 for the glass to scatter. It also serves to co-operate with the shoulders of different bottles having necks of different lengths. Where the neck of the bottle is short the plate 38 will be moved much further to the right in Figure 3, 30 whereas when the neck of the bottle is long, as shown in the drawing, the plate is moved only a slight distance. It any case, therefore, this movable plate will form a closing wall on one side of the housing to prevent the escape of the 35 breaking glass.

The more important feature of my invention resides in the co-operation of an anvil member which is received within the neck of the bottle and the fracturing member disposed outside the 40 neck of the bottle and co-operating with the anvil to break the portion of the neck lying between these two members. It requires much less force for these two members to fracture the intervening glass than would be required to fracture 45 the glass by members lying entirely exterior of the neck of the bottle. It is preferable to have the anvil and the plunger contact with the neck of the bottle on three lines of contact, as illustrated in Figures 4 and 5 in order to apply 50 the breaking force in a manner which will fracture the intervening glass with a minimum of power applied.

The present device is adapted to operate on various types of bottles. In all cases the bottle neck has a bore into which the anvil may be received.

The external plunger is withdrawn from the 5 anvil a sufficient distance to receive any type of bottle neck between the anvil and the plunger. The present device will operate on bottle necks having screw threads or flanges of different kinds so that the device is of universal use. 10

Having described my invention, what I claim is:

1. A bottle breaking machine including a 15 housing, an anvil member adapted to be received into the bore of a bottle neck presented thereto, a member exterior of the bottle neck and co-operating with said anvil to fracture the intervening glass of the bottle neck, one wall of said housing being movably mounted for lateral movement toward and from said anvil member, 20 resilient means tending to move said movable wall away from said anvil, said movable wall having an aperture of sufficient size to receive the neck of a bottle therethrough for presentation of the bottle neck over said anvil, said aperture being so proportioned that the shoulder of the bottle will engage said movable wall and move said movable wall until the outer end of the bottle neck is presented over said anvil. 25

2. A bottle breaking machine including a 30 housing, an anvil member adapted to be received into the bore of a bottle neck presented thereto, a member exterior of the bottle neck and co-operating with said anvil to fracture the intervening glass of the bottle neck, one wall of said housing being movably mounted for lateral movement toward and from said anvil member, resilient means tending to move said movable wall away from said anvil, said movable wall having an aperture of sufficient size to receive 40 the neck of a bottle therethrough for presentation of the bottle neck over said anvil, said aperture being so proportioned that the shoulder of the bottle will engage said movable wall and move said movable wall until the outer end of 45 the bottle neck is presented over said anvil, and a guiding member extending from said anvil and receivable within the neck of the bottle for guiding the neck over said anvil. 50

JOSEPH MORENG.
